ADJUSTABLE FISHING REEL SEAT

Filed Jan. 17, 1947

FIG. 1

FIG. 2

INVENTOR.

Charles H. Matson

UNITED STATES PATENT OFFICE

151,649

DESIGN FOR AN ADJUSTABLE FISHING REEL SEAT

Charles H. Matson, New York, N. Y.

Application January 17, 1947, Serial No. 136,215

Term of patent 14 years

(Cl. D31—4)

To all whom it may concern:

Be it known that I, Charles H. Matson, a citizen of the United States of America, residing at New York city, in the county of New York and State of New York, have invented a new, original, and ornamental Design for an Adjustable Fishing Reel Seat, of which the following is a specification, reference being had to the accompanying drawing, forming part thereof.

In said drawing:

Figure 1 is a top plan view of an adjustable fishing reel seat, showing my new design; and
Figure 2 is a side elevational view thereof.

I claim:

The ornamental design for an adjustable fishing reel seat, as shown.

CHARLES H. MATSON.
